UNITED STATES PATENT OFFICE.

SYVER LOE, OF MINNEAPOLIS, MINNESOTA.

REGISTER-ACTUATING MECHANISM.

1,229,301.

Specification of Letters Patent. Patented June 12, 1917.

Application filed August 6, 1914. Serial No. 855,393.

To all whom it may concern:

Be it known that I, SYVER LOE, a citizen of the United States, residing at Minneapolis, in the county of Hennepin and State of Minnesota, have invented certain new and useful Improvements in Register-Actuating Mechanism; and I do hereby declare the following to be a full, clear, and exact description of the invention, such as will enable others skilled in the art to which it appertains to make and use the same.

Broadly, my present invention has for its object to provide an extremely simple and highly efficient device for transferring vibratory motion into rotary motion. Particularly, it has for its object to provide an improved device for actuating the registers, which involve a plurality of wheels arranged to carry in a decimal order from one to the other.

In the accompanying drawings which illustrate the invention, like characters indicate like parts throughout the several views.

Referring to the drawings:

Figures 1 and 2 are views in front elevation showing the improved device, and illustrating different positions of the actuating lever; and

Fig. 3 is a plan view of the parts shown in Figs. 1 and 2, some parts being broken away.

The register which may be assumed to be of the Veeder type, has a casing 1 within which is a plurality of register wheels 2 of well known construction and arrangement. The unit member of the register wheels 2 is connected, as shown, by a toothed or serrated hub 3, to an escapement wheel 4 which has a plurality of circumferentially spaced laterally projecting escapement lugs 5 that are V-shaped in the plane of the said escapement wheel.

The escapement lever 6 is stamped from a single piece of metal, preferably of steel, and at its intermediate portion is laterally bent or offset, and formed at its offset portion with reversely projecting sharp pointed pallets or cam lugs 7. At one end, the lever 6 is pivotally connected to a stud 8 that is secured to a bracket 9 rigidly fastened to the casing 1.

The escapement device is operated by imparting oscillatory or vibratory movements to the escapement lever 6, and this movement may be imparted to the said lever in various different ways.

Under upward movement of the lever 6,

the upper pallet 7 will engage an overlying escapement lug or tooth 5 and impart a half step movement to the escapement wheel, and under downward movement of the said lever the lower pallet will engage the underlying lug 5 and impart the second half step of movement to the said escapement wheel. One complete two-step escapement movement will move the escapement wheel one tenth of a complete rotation, or far enough to register one unit of movement on the unit wheel 2 of the register.

The pointed form of the escapement lugs 5 and of the pallet 7 makes it impossible for the escapement lever to become locked against proper oscillatory movements. When one pallet is moved out of engagement with one escapement lug, the other pallet is moved into engagement with a diametrically opposite escapement lug, and in fact, the engagement of the one pallet with an escapement lug will start a movement of the escapement wheel before the other pallet is moved from between the two opposite escapement lugs, which action is clearly shown in Fig. 2. When the lever is in an extreme position, one of its pallets will engage solidly between two escapement lugs and securely hold the escapement wheel against movement in either direction.

By reference particularly to Fig. 3, it will be noted that both ends of the lever 6 lie in the same plane, while the pallets are offset just far enough for engagement with the escapement lugs of the escapement wheel.

The purpose of the teeth or serrations 3 and hub or shaft of the unit member of the register wheels, is to facilitate re-setting of the register, simply by drawing a thin strip 95 of wood, the edge of a card board, or the like, over the said hub, thereby imparting rapid backward rotation to the unit member of the register wheels. Such backward movement will, of course, cause a rapid vibration of the escapement lever since the beveled form of the backs of the escapement lugs and of the faces of the pallets 7 are such as to produce a camming action required to vibrate the lever.

In practice, I have found that the V-shaped or triangular cam lugs operate with perfect satisfaction, whereas, an escapement wheel with studs or round projections or pins will frequently lock the lever against vibration and prevent the desired operation of the escapement device.

2
What I claim is:

In a mechanism for converting reciprocating movement into step by step rotary movement, the combination with an escapement wheel and a vibratory escapement lever operative thereon to produce a step by step rotary movement thereof, of a rotated wheel laterally spaced from said escapement wheel, and a serrated hub located between

and rigidly connecting said rotated wheel 10 and escapement wheel and serving the function set forth.

In testimony whereof I affix my signature in presence of two witnesses.

SYVER LOE.
